(57) **CLAIM**

The ornamental design for a pill crushing cup base, as shown and described.

DESCRIPTION

FIG. 1 is a perspective view of the top of a pill crushing cup base showing our new design;

FIG. 2 is a plan view showing the inside thereof;

FIG. 3 is a bottom view thereof;

FIG. 4 is a perspective view of the bottom thereof; and,

FIG. 5 is a side elevation view thereof.

The dashed lines depict environmental subject matter, specifically the upper portion of the pill crushing cup and markings thereon. The dot-dash lines are boundaries limiting the extent of the claimed subject matter. The dashed and dot-dash lines form no part of the claimed design.
